ANNEALING BOX

Percy E. Hunter and Kenneth J. Deahl, Pittsburgh, Pa.; said Deahl assignor to said Hunter

Application February 17, 1936, Serial No. 64,329

9 Claims. (Cl. 263—49)

This application is a continuation in part of our application Serial No. 40,882, filed September 17, 1935, and relates to annealing boxes employed in the heat treatment of metal, and is 5 hereinafter described as of the sheet metal type.

Annealing boxes as heretofore constructed represent a considerable initial investment and are short lived and have to be replaced very frequently, since they will retain their shapes and 10 effectiveness for only a very limited number of "heats". The roofs or tops thereof in time become permanently sagged to such an extent that they will no longer accommodate a desired "charge" of material to be treated. Furthermore, 15 the sides will become bulged, and otherwise distorted, so that the boxes cannot be placed in the furnaces. Also, distortions through unequal temperature changes frequently are so pronounced that cracks and fissures develop in the 20 walls of the boxes.

One object of our invention is to provide an 25 annealing box structure of such form that the distortions through temperature changes are confined to definite lines of bend, about which lines the metal will flex both when expanding and contracting, so that the walls of the box will 30 always return to approximately their original positions, upon cooling.

Another object of our invention is to so design 35 the box that the bending or distortion through temperature changes can take place in various portions of the box without creating excessive strains at other portions or at the juncture of cooler and hotter portions.

Still another object of our invention is to provide a reinforcing element of hollow form so constructed and arranged that the box is adequately 40 reinforced against distortion in the vicinity where a portion of the box that becomes very highly heated in use adjoins another lower portion thereof that normally does not become heated to a very high temperature.

Some of the forms which our invention may 45 take are shown in the accompanying drawings wherein Figure 1 is a longitudinal sectional view, through an annealing box; Fig. 2 is an end view thereof, partially in section; Fig. 3 is a fragmentary plan view; Fig. 4 is an enlarged view taken on the line IV—IV of Fig. 3; Fig. 5 is a 50 fragmentary longitudinal sectional view of a modified form of box; Fig. 6 is a fragmentary side view of another form of box, partially in section; Fig. 7 is an enlarged view taken on the line VII—VII of Fig. 6; Fig. 8 is a view taken on the line VIII—VIII of Fig. 7; Fig. 9 is a view simi-

lar to Fig. 8, but showing another modification, and Fig. 10 is a similar view showing still another form.

Referring first to Figs. 1 to 5, the box is shown as constructed of sheet metal, but it will be understood that various features of the invention are applicable also to boxes formed of cast metal. The box is provided with side walls 10, end walls 11, and a top wall 12, formed of plates which are welded together at their abutting edges to produce a unitary box structure.

The walls of the box are so shaped as to have inwardly and outwardly-exposed channels, 13 and 14 formed therein that are substantially coextensive with the walls of the box, the channels in the side walls matching the channels in the top wall and being in effect continuous therewith. These channels, of course, serve to stiffen the structure and enable it to be made of lighter gauge material than would otherwise be 20 possible.

The temperature changes to which the box is subjected are, of course, very great, and the tendency toward distortion or deformation is very great, owing to the fact that parts of the box become heated or cooled much more quickly than other parts thereof. If the distortional movements are confined to certain zones or lines, the parts of the box will, after expansion under heat, be restored to approximately their original position and shape upon cooling.

In the present case, the bending movements will occur at and adjacent to the lines of corners 16 and 17 of the various channels, and this result is secured by stiffening the webs or bottom walls of the channels by striking up grooves or depressions 18 therein along lines, extending transversely of the channels.

It will be seen that when the box expands through the application of heat, it will bend much more readily along the lines 16 and 17 than along lines extending longitudinally of the bottom walls of the channels, since the grooves or struck-up ribs 18 will resist bending on such median lines of the channels. When the box cools, bending will occur in the reverse directions along the lines 16 and 17, and the box assumes approximately its original shape.

A sufficient number of reinforced channels are provided to insure that the total of expansive movement is distributed at sufficiently numerous points to prevent excessive strain of the metal in any one area. It will be understood that the webs of the channels can be reinforced by means other than the depressions 18, as by means of small 50 55 60 65 70 75 80 85 90 95 100 105 110 115 120 125 130 135 140 145 metal members 18a welded to the webs of the channels, at suitable points as in Fig. 5.

Another difficulty encountered in the use of annealing boxes is that of the roof sagging in such manner that it not only extends too low into the box, but causes bulging and distortion of the sides of the box. To overcome this difficulty, I supplement the roof channels by supporting elements which can rest upon the pack of sheets 10 or other material in the box. At various suitable points in the top wall of the box, I provide sleeves 20 through the bottom walls of which extend studs or pins 21 which may suitably be of refractory material such as clay or metal of 15 low thermal conductivity. The stud 21 is provided with a head which will prevent its falling out of the sleeve 20, but is loosely supported in the sleeve. An air seal 22 of sand or other suitable material is placed above the stud 21.

20 An adjustable locking element 23 is provided for limiting the upward movement of the stud 21, so that adjustments can be made whereby the stud 21 will be limited in its upward movement, and thereby permit adaptation of the supporting device to sheet packs 25 of various heights 25 within the box.

The member 23 is held in various adjustable positions by means of a pin 24 that extends through walls of the sleeve 20, to engage grooves 30 in the member 23. It will be understood that with the parts in the position shown in Fig. 4, the top wall 12 will be held against sagging by the stud 21.

Annealing boxes commonly have their lower 35 edges resting in and sealed by a body of sand 28, and the furnace heat usually impinges against the box at points some distance above the sand. The result is that there is a wide difference in temperature as between the upper portions of the 40 box and the lower edges thereof.

At approximately the line of greatest difference in temperature, we provide a hollow rib-like reinforcing element 28 that extends peripherally of the box and functions as a stiffening rib. 45 In prior structures these peripherally-extending ribs have usually been formed by simply forming a groove or channel in the side and end walls of the box, the groove being exposed inwardly. Frequently, the difference in temperature between the upper and lower edges of the grooves 50 or channels is so great that excessive distortion of the box occurs in the vicinity of the channel. In order to more nearly equalize and distribute the temperatures at the zone, we apply the reinforcing channel 28 to the outside of the walls 55 of the box. The edges of the channel-like element 28 are welded to the box walls and the flanges thereof are cut away so as to fit the outwardly-protruding channels 13.

60 In order to compensate for weakening of the channel 28 which is caused by cutting it away where it extends across the channels 13, at those points, we weld strengthening plates 30 to the inner walls of the box.

65 Referring now to Figs. 6, 7, and 8, we show a box which corresponds somewhat to the box shown in Figs. 1, 2, and 3, but wherein the peripheral channel 33, which corresponds somewhat to the peripheral channel or groove member 70 28 has its edges welded to the side and end sheets of box, and has its flanges cut away so that they will snugly fit the outer surfaces of the ribs 32 which correspond to the ribs or corrugations 13 of Fig. 1. In order that there will be no confinement of air within the peripheral rib 33 and

consequent tendency to overheating of the rib, holes 34 are provided in the rib, at suitably spaced points.

At points generally opposite to where the channels 33 are cut away to fit the hollow ribs 32, we weld small plates or bars 35 to the inner wall of the box which members serve as tie elements or stiffening members to resist deformation of the box at those points.

In Figure 9, we show a peripheral channel 37, 10 which corresponds to the channel 33, but which is set between and welded to upper plates 38 and lower plates 39. These plates or sheets may be of the same form as the side walls of the box shown in Figs. 1, 2, 8. The channel 37 is therefore exposed inwardly to the box and no holes such as the holes 34 are required in order to avoid the confinement of air in the channel. The depths of the vertical corrugations in the sheets 38 and 39 are so great as to overlie the 20 major portion of the channel 37, whereby these members reinforce one another and a tie plate at the inner wall will not usually be required.

Referring now to Fig. 10, I show a structure similar to that of Fig. 9, but wherein the depth 25 of the channel 41 and the depth of the corrugated plates 42 and 43 differ to such extent that the corrugations overlie only about one-half of the width of the channel 41, wherefore, short stiffening plates or bars 44 are welded to the 30 inner wall of the box at suitable intervals to strengthen the channel.

We claim as our invention—

1. An annealing box of sheet-metal, having channels formed in its walls, the web portions 35 of the channels being provided with elongated depressions extending transversely thereof.

2. An annealing box of sheet-metal, having channels formed in its walls, adjacent channels being exposed inwardly and outwardly, respectively, and merging with one another, and means for stiffening the channels against bending movements along longitudinally-extending areas between the zones of said merging.

3. An annealing box having a peripherally-extending reinforcing channel disposed exteriorly 45 of the box, along horizontal lines located adjacent to, but a substantial distance above the lower edge of the box, the flanges of the channel being welded to the sides of the box.

4. An annealing box having vertically-extending corrugations in its side walls and provided with a horizontally-extending reinforcing channel on its exterior surfaces, the channel having its flanges welded to said surfaces and portions 55 of its flanges being cut away to fit the corrugations.

5. An annealing box having a hollow rib disposed peripherally thereof in a plane adjacent to, but located at a substantial distance above the lower edge of the box, the rib having its edges abutting the outer wall surfaces of the box, and being provided with openings to the atmosphere.

6. An annealing box having upper and lower side wall portions provided with vertically-extending corrugations, and hollow ribs interposed between the adjacent edges of said portions and secured to the ends of said corrugations.

7. An annealing box having upper and lower side wall portions provided with vertically-extending corrugations, and hollow ribs interposed between the adjacent edges of said portions and secured to the ends of said corrugations, the inner edges of the ribs being substantially flush with the inner faces of said wall portions.

8. An annealing box of sheet metal, having channels in certain of the wall areas, the bottom walls of the channels having transversely-extending stiffening devices thereon at various 5 points throughout the length of the channels.

9. An annealing box having upper and lower side wall portions provided with vertically ex-

tending corrugations, hollow ribs interposed between the adjacent edges of said portions and secured to the ends of said corrugations, and tie members secured to and bridging the inner edges of the ribs.
